WORK-JOGGING ATTACHMENT FOR SEWING MACHINES

John P. Enos, Union, N. J., assignor to The Singer Manufacturing Company, Elizabeth, N. J., a corporation of New Jersey

Application October 8, 1954, Serial No. 32,602

Term of patent 14 years

(Cl. D70—2)

Fig.1

Fig.2

Fig.3

Fig. 4

Fig. 5

Fig. 6

Fig. 7

Fig. 1 is a front perspective view of a work-jogging attachment for sewing machines embodying my new design;

Fig. 2 is a rear perspective view;

Fig. 3 is a top plan view;

Fig. 4 is a right side elevational view;

Fig. 5 is a left side elevational view;

Fig. 6 is a front elevational view; and

Fig. 7 is a rear elevational view.

What I claim herein is:

The ornamental design for a work-jogging attachment for sewing machines, substantially as shown.
